UNITED STATES PATENT OFFICE.

FREDERIC TUDOR, OF BROOKLINE, MASSACHUSETTS, ADMINISTRATOR OF
FREDERIC TUDOR, DECEASED.

VALVE.

SPECIFICATION forming part of Letters Patent No. 759,774, dated May 10, 1904.

Application filed March 5, 1903. Serial No. 146,424. (No model.)

To all whom it may concern:

Be it known that FREDERIC TUDOR, late a citizen of the United States, and a resident of Brookline, in the county of Norfolk and State of Massachusetts, did invent new and useful Improvements in Valves, of which the following is a specification.

This invention relates to valves generally, but particularly to valves for use in low-pressure steam-heating systems, and the principal object of the invention is to provide an improved valve for controlling the passage of the heating agent from the supply to the radiator of a heating system, and one whose capacity may be varied to adapt it to radiators of different sizes or capacity.

In Patent No. 705,981, dated July 31, 1902, there is shown and described a low-pressure steam-heating system embodying a valve of the above character for controlling the passage of the steam from the supply to the radiator, and herein is shown an invention as embodied in a valve of the same type as that shown in the patent aforesaid. It is not, however, considered that this invention is limited to the particular embodiment herein shown and described.

Valves of this type have heretofore been operated by means of a cam having a fixed or unchangeable throw, and consequently the scope of graded and economical steam-delivery of such valves has heretofore been limited to radiators having a condensing capacity no greater than the capacity of the valve when in its fully-open position. The capacity of a given valve when in its fully-open position was of course limited to and determined by the extreme throw of the cam. Therefore a valve having a cam of a given unchangeable throw was limited in its use to radiators having no greater condensing capacity than that for which cams of that particular throw were appropriate. It is also true of valves of this type that as heretofore constructed when a valve of a given capacity was used with radiators having a maximum condensing capac-

ity less than that for which the fully-open position of the valve was appropriate the usual index or dial of that valve would not be appropriate to that radiator and would falsely indicate the one-fourth, one-half, three-fourths, and fully-open positions of the valve for that particular radiator, for when in the fully-open position according to the index the valve would have too great capacity for the maximum condensing capacity of the radiator. Thus in order to provide a fully-efficient equipment for radiators of miscellaneous sizes it has been necessary to provide valves with cams graded to suit gradations in radiator-surfaces, and thus either a large stock of valve-cams has been required or else special construction of cams resorted to. These features, which are objectionable, are obviated by the present invention, which is an improved valve provided with an adjustable valve-operating cam and with means for holding the cam in adjusted position, whereby the maximum throw of the cam, and therefore the maximum capacity of the valve, may be varied at will to suit the valve to the condensing capacity of the radiator with which it is used and whereby one and the same index will serve for all adjusted positions of the cam.

In the preferred form of the invention as herein shown and described the valve-operating cam is hinged to its support near the point of the cam corresponding to the closed position of the valve and is supported by an adjustable screw, by means of which the cam is held in adjusted position.

In the accompanying drawings, which illustrate an embodiment of the invention, Figure 1 is an elevation of a valve embodying the preferred form of the invention. Fig. 2 is a central longitudinal section of the valve shown in Fig. 1. Fig. 3 is a plan view of the cam and dial detached. Figs. 4 and 5 show modifications.

Having reference to the drawings, C represents the casing of the improved valve, and V the valve proper. The valve-stem V² extends

through the stuffing-box C to the exterior of the casing C and at its outer end has fixed to it a handle H. Mounted on the stuffing-box C² is a dial F, marked, as usual, to indicate 5 "shut," "one-fourth open," "one-half open," "three-fourths open," and "open" positions of the valve V by the registering therewith of a pointer h on the handle H. Upon the top face of dial F is provided an annular or 10 crown-shaped cam K, and against this cam K a projection k on the handle H is held by a spring S, which moves the valve V in one direction, while by rotating the handle H and causing the projection k to traverse cam K 15 the valve V is moved by the cam K in the opposite direction. The annulus which makes up the cam K is slotted transversely of its axis, as at k', so as to leave a flexible hinge k², connecting the annulus with the dial, and this 20 hinge is preferably located near the lowest point of the cam—that is, opposite the point on the dial marked "Shut." That part of the annulus below the cam K and slits k' is tapped to receive a capstan-screw k⁴, whose head bears 25 against the under side of and supports the cam K. By means of a suitable tool the capstan-screw k⁴ may be rotated to raise and lower it in its screw-threaded socket, and when raised or lowered of course the cam K 30 will be swung on its hinge k², which, as stated, is near the lowest portion of the cam K, and as a result the part of the cam opposite the point marked " $\frac{1}{4}$ " on the dial will be raised or lowered, according to the direction in which 35 the capstan-screw k⁴ is turned. In the valve-cam herein shown the part opposite the word "Open" is given extra pitch for emergency opening of the valves for purposes described in the patent aforesaid. This abrupt pitch is 40 sufficient for all adjusted positions of the cam-annulus.

In Fig. 4 is shown another form of the invention wherein the annulus which makes up the hinged cam K is split alongside the web k⁵, 45 as at k³, so that one end of the split annulus is fastened to the dial F by the web k⁵, and the other free end is supported by the adjustable capstan-screw k⁴.

In Fig. 5 the cam K is shown as a separate 50 piece hinged to the dial F by the pintle k⁶.

The improved valve is particularly adapted to be used in low-pressure steam-heating systems to control the passage of the steam from the supply to the radiator, and by the improvements the capacity of a single valve may 55 be adjusted to suit or be appropriate to radiators of almost any condensing or heat-radiating capacity, as it will now be clear that by means of the capstan-screw k⁴ the cam K may 60 be adjusted on its hinge k² or web k⁵, so as to increase or diminish the throw of the cam and

make its greatest throw appropriate to the maximum condensing capacity of the radiator with which it is to be used. This adjustment of the throw of the cam K not only adjusts 65 the capacity of a given valve to radiators of different sizes, but as the maximum condensing capacity of radiators varies with the surrounding temperature this adjustment permits the valve to be regulated to accord with 70 the temperature surrounding the radiator or with the general condition of the weather or advancing seasons. It will also be clear now that this adjustment of the cam K does not call for adjustment of dial F or for the substitution of another dial, but that the same 75 dial will serve as a truthful index for all positions of the cam K.

What is claimed is—

1. The combination of a valve, its stem, and 80 a stem-operating cam, the stem and cam relatively movable to actuate the valve, a stationary cam-support whereon the cam is hinged, and means for adjusting the cam upon its hinge. 85

2. A valve-operating device comprising a cam adjustable to vary its throw; a stationary support for the cam, a hinge connecting the cam and support; means for adjusting the relative positions of the cam and support, and 90 a valve-stem controlled by the cam.

3. A valve-operating device comprising a cam, a support therefor; a flexible connection between the cam and support integral with both, adjusting means to determine the pitch 95 of the cam with relation to the support, and a valve-stem controlled by the cam.

4. In a valve, the combination with a stem provided with a shoulder, of a hinged cam with relation to which the stem is rotatable, 100 said cam directly engaging the shoulder to move the stem endwise when the latter is rotated relatively to the cam, and means to adjust the cam on its hinge to vary the throw of the cam. 105

5. In a valve, the combination with the valve-stem, of a cam with relation to which the stem is rotatable, said cam adapted to move the stem endwise when the latter is rotated relatively to the cam; a support for the 110 cam; a spring-hinge rigidly connected at one end to the cam and at its other end to the support, and means to adjust the cam on the spring-hinge to vary the throw of the cam.

6. In a valve, the combination with the 115 stem, of a split flexible cam-ring with relation to which the stem is rotatable, said cam-ring adapted to move the stem endwise when the latter is rotated relatively to the cam-ring; a support to which one end of the cam-ring is 120 fastened, and means to bend the cam-ring to vary the throw thereof.

7. In a valve, the combination with the stem, of a split flexible cam-ring with relation to which the stem is rotatable, said cam-ring adapted to move the stem endwise when the latter is rotated relatively to the cam-ring; a support; a spring-hinge rigidly connected at one end to the cam-ring and at its other end to the support, and means to bend the cam-ring and hinge to vary the throw of the cam.

Signed at Boston, Massachusetts, this 20th ¹⁰ day of February, 1903.
